DESIGN FOR A DRESS

Adele Ofshe, New York, N. Y.

Application January 16, 1940, Serial No. 89,494

Term of patent 3½ years

To all whom it may concern:

Be it known that I, Adele Ofshe, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

I claim:

The ornamental design for a dress, substantially as shown.

ADELE OFSHE.
